Specification for Design.

Patented May 9, 1916.

Application filed October 21, 1912. Serial No. 727,086. Term of patent 14 years.

To all whom it may concern:

Be it known that I, JOHN M. VAN HEUSEN, a citizen of the United States, residing at Boston, in the county of Suffolk, State of Massachusetts, have invented a new, original, and ornamental Design for Combination-Garments, of which the following is a specification, reference being had to the accompanying drawing, forming part thereof.

I claim—

The ornamental design for a combination garment, as shown.

In testimony whereof, I have hereunto attached my signature, in the presence of two witnesses.

JOHN M. VAN HEUSEN.
